US00D996619S

(12) **United States Design Patent** (10) Patent No.: **US D996,619 S**
Wallach et al. (45) Date of Patent: **** Aug. 22, 2023**

(54) **DEVICE THAT MEASURES EXHALATION DURATION**

(71) Applicant: **Dendro Technologies, Inc.**, New York, NY (US)

(72) Inventors: **Adi Wallach**, New York, NY (US); **Elisha Tal**, Nataf (IL); **Michael Yakoby**, Kfar Saba (IL); **Raz Moheban**, Shoshanat Haamakim (IL)

(73) Assignee: **Dendro Technologies, Inc.**, New York, NY (US)

(**) Term: **15 Years**

(21) Appl. No.: **35/514,293**

(22) Filed: **Jan. 4, 2022**

(80) **Hague Agreement Data**

Int. Filing Date: **Jan. 4, 2022**

Int. Reg. No.: **DM/220656**

Int. Reg. Date: **Jan. 4, 2022**

Int. Reg. Pub. Date: **May 20, 2022**

(51) **LOC (14) Cl. 24-02**

(52) **U.S. Cl.**

USPC **D24/164**; D10/40

(57) **CLAIM**

The ornamental design for a device that measures exhalation duration, as shown and described.

DESCRIPTION

1. Device that measures exhalation duration

1.1: Perspective

1.2: Right

1.3: Left

1.4: Front

1.5: Back

1.6 : Top

1.7 : Bottom

The broken lines are for the purpose of illustrating the position of electrodes that form no part of the claimed design.

1 Claim, 7 Drawing Sheets
